(57) **CLAIM**

We claim the ornamental design for a panoramic imaging system, as shown and described.

DESCRIPTION

FIG. 1 is a top, front, and left side perspective view of a panoramic imaging system, shown with the internal structures through the translucent outer surfaces omitted for ease of illustration;

FIG. 2 is a top plan view thereof;

FIG. 3 is a front elevation view thereof;

FIG. 4 is a left side elevation view thereof;

FIG. 5 is a right side elevation view thereof;

FIG. 6 is a rear elevation view thereof;

FIG. 7 is a bottom plan view thereof; and,

FIG. 8 is a rear elevation view of the panoramic imaging system of FIG. 1, shown with the internal structures visible through the translucent outer surfaces of the panoramic imaging system.

The broken lines depict portions of the panoramic imaging system that form no part of the claimed design.
